(57) **CLAIM**

The ornamental design for a mounting bracket for magnetically attracted lighting device, as shown and described.

DESCRIPTION

FIG. 1 is a front perspective view of a mounting bracket for magnetically attracted lighting device in accordance with an embodiment of the present invention.

FIG. 2 is a top view thereof;

FIG. 3 is a front view thereof;

FIG. 4 is a side view thereof; and,

FIG. 5 is a bottom view thereof.

The dot-dash broken lines immediately adjacent the shaded areas represent the bounds of the claimed design while all other broken lines are directed to unclaimed portions of the article. The broken lines form no part of the claimed design.
